[57] CLAIM

The ornamental design for a repaired electrical appli-
ance tester, as shown and described.

DESCRIPTION

FIG. 1 is a front-top perspective view of my new re-
paired electrical appliance tester design, with the cover
of the housing closed;

FIG. 2 is a rear-top perspective view thereof;

FIG. 3 is a perspective view thereof with the cover
open;

FIG. 4 is a rear and bottom perspective view thereof
with the cover open;

FIG. 5 is a perspective view of my new testing device
design, with the cover of the housing open and showing
the disposition of a remote key-pad in the cover lid of
the housing;

FIG. 6 is a view similar to that of FIG. 5 with the key-
pad removed; and,

FIG. 7 is a perspective view of my design carried by an
operator.

The broken line showing of a human is for illustrative
purposes only and forms no part of the claimed design.
